[57] CLAIM

The ornamental design for a catheter adapter, as shown and described.

DESCRIPTION

FIG. 1 is a perspective view of a catheter adapter showing our new design;

FIG. 2 is a side elevational view thereof, the opposite side view being a mirror image thereof;

FIG. 3 is a left end elevational view thereof;

FIG. 4 is a right end elevational view thereof; and,

FIG. 5 is a top plan view thereof, the bottom plan view being a mirror image thereof.
